SEAT CUSHION HAVING HELPER PAD AND SPRING-OVER-SPRING STRIP BASE

Hyland C. Flint, Birmingham, Mich., assignor to American Metal Products Company, Detroit, Mich., a corporation of Michigan

Application April 19, 1949, Serial No. 88,292

6 Claims. (Cl. 155—181)

1

This invention relates to spring constructions and, in particular, to spring constructions which embody a plurality of pre-arched sinuous or zig-zag spring strips of the type disclosed and claimed in Kaden Reissue Patent No. 21,263.

In spring constructions of the type indicated, particularly those employed as back rests, it is sometimes desirable to vary the character and contour of the resilient surface in order to provide improved support for and conformation to the human back. According to the present invention a direct approach to the problem is made by the use of flexible padding to build up desired areas of the resilient surface, sinuous spring elements being employed to hold the padding in place.

It is thus the object of the invention to provide a sinuous spring construction which is especially adapted to support the human back in a comfortable manner.

Preferred embodiments of the invention are shown by way of illustration in the accompanying drawings in which:

Figure 1 is a plan view or front elevation of a portion of the improved spring construction;

Fig. 2 is a section along the line 2—2 of Fig. 1, which is extended to show the frame and the attachment of the sinuous spring strips thereto; and

Fig. 3 is a partial side elevation of a modified form of the invention.

The spring construction includes a frame 1 to which the upper and lower supports 3 and 5 of the laterally spaced sinuous spring strips 7 are secured by means of clips 9. The webs 11 of the strips 7 form, in combination, a resilient surface which may be covered by suitable fabric and upholstery to make it soft and attractive.

The resilient surface is built up by means of flexible padding 13 which, in Fig. 2, lies on the underside surfaces of the webs 11. The padding may be formed of various materials such as foamed rubber or, as illustrated, of stepped layers 15 of jute, cotton, and the like sewn in a fabric cover 17. These pads have a height which, of course, is dependent upon the extent of desired reinforcement and extend laterally of the spring strips 7. Preferably, they are laterally spaced and slotted, as shown at 19, so as to provide room for flexing and lateral expansion.

The padding 13 is held in place by sinuous helper spring elements 21 which overlie the pads and are secured at each end by clips 23 to the webs 11 of the strips 7. The elements 21 are preferably pre-arched on an arc of lesser radius than that

2

which they have when secured to the webs, as indicated by the dotted contour of a free element 21 in Fig. 2 prior to its final connection to the strip 7, and the elastic deformation in assembly of the elements 21 may be sufficient to reverse the contour from convex to concave as shown. The helper elements 21 are thus in a stressed condition attempting to return to their original formation and this serves to tightly hold the padding 13 in place as well as endow the springs 21 themselves with a desirable resiliency. It will be recognized that the helper springs 21 and padding 13 will stiffen the resilient surface provided by the webs 11 so as to give desirable support to human vertebrae but are nevertheless sufficiently flexible to provide comfort also.

In the embodiment of Fig. 3, the padding 13 is applied to the outer sides of the webs 11 and therefore varies the contour of the resilient surface. The helper spring elements 25 are pre-formed on a relatively small radius, as indicated by the dotted lines, and then stretched to a larger radius on the same center by attachment to the webs 11 through the medium of the clips 23. In this form of the invention the padding 13 not only increases the stiffness of the spring construction, as indicated in the preceding embodiment, but also provides a simple means of adjusting the contour to a desired shape.

It will be apparent that other modifications may be made within the scope of the invention.

What is claimed is:

1. In a spring construction, the combination of a frame, a plurality of laterally spaced sinuous springs secured to the frame, said springs having webs cooperating to provide a resilient surface, a pad applied to said surfaces, and sinuous spring elements secured at their ends to said webs and overlying said pad to hold it against the webs.
2. The invention as claimed in claim 1 wherein said pad and elements are on the inside of the webs.
3. The invention as claimed in claim 1 wherein said pad and elements are on the outside of the webs.
4. In a spring construction, the combination of a frame, a plurality of laterally spaced sinuous springs secured to the frame, said springs having webs cooperating to provide a resilient surface, a pad applied to said surface, and sinuous spring elements secured at their ends to said webs and overlying said pad to hold it against the webs, said sinuous spring elements being preformed on a lesser radius than that which they have when secured to the webs.

5. In a spring construction, the combination of a frame, a plurality of laterally spaced sinuous springs secured to the frame, said springs having webs cooperating to provide a resilient surface, flexible padding on said webs having laterally spaced expansion and contraction slots, and sinuous spring elements parallel with said webs and secured thereto, said padding being between the elements and webs.

6. In a spring construction, the combination of a frame, a plurality of sinuous springs supported by said frame, one group of said springs being disposed above another group of said springs, and a pad disposed between said groups of springs.
